UNITED STATES PATENT OFFICE.

JOHN DENTON, OF PATERSON, NEW JERSEY.

FLUSHING APPARATUS.

1,149,430.

Specification of Letters Patent. Patented Aug. 10, 1915.

Original application filed March 6, 1913, Serial No. 752,323. Divided and this application filed November 11, 1914. Serial No. 871,470.

To all whom it may concern:

Be it known that I, JOHN DENTON, a citizen of the United States, residing at Paterson, in the county of Passaic and State of New Jersey, have invented certain new and useful Improvements in Flushing Apparatus, of which the following is a specification.

This invention relates to flushing apparatus of the type in which means is employed for mechanically lifting the body of water in the short leg of the siphon over the bend and into the long leg of the siphon for the purpose of starting the siphon action. Where the fall of the long leg of a siphon is short, as in the use of so-called "low-down" tanks, it is necessary that the working movement of the lifting means should accomplish as complete an exhaustion of the short leg as possible; that at the end 20 of the lifting stroke said means should be adapted to allow the water in the tank to pass through the siphon with as little opposition as possible; and that finally, when the lifting means returns to the rest position it 25 should at once assume the condition rendering it fully effective for the next siphon starting action. Due to the absence of one or more of these qualities flushing apparatus of this character heretofore devised have 30 been unreliable and frequently operate with at best but a sluggish siphoning action.

My object is to provide a lifting means for siphon flushing apparatus of the kind referred to which shall be adapted to exhaustively displace the water from the short leg of the siphon on the working stroke, thereupon allow perfectly unobstructed passage of the water in the tank through the siphon, and finally assume automatically 35 that state or condition which renders it effective to perform properly the next lifting operation.

The present application is a division of that upon which issued to me Letters Patent No. 1,109,971, dated September 8th, 1914.

In the accompanying drawings, Figure 1 is a side elevation, partly broken away, of the improved flushing apparatus; Fig. 2 is a vertical sectional view on the line y—y 50 of Fig. 3; and, Fig. 3 is a horizontal sectional view through the short leg of the siphon and the lifting means.

As in my Patents Nos. 768,215 and 833,681 the siphon includes with the long leg a,

penetrating and suitably secured in the bottom wall of the tank b, a short leg c which is appreciably greater in diameter than the leg a and in the present instance consists of a cylinder which is screwed into the neck or bend-member d of the siphon, in turn screwed 55 upon the upper end of the leg a. The part of the member d into which the cylinder c is screwed is a relatively offset portion d' of member d forming a top wall or cap for the cylinder c of such form that the 60 longitudinal axis of the cylinder passes through the cap exteriorly of the body part of the member d. Axially of the cylinder there is arranged in the cap d' a downwardly depending tube f. Through this 65 tube extends the stem g of the lifting means also including a piston h attached to the lower end of the stem and to be described in detail.

i is a handle (in this case a short lever 75 fulcrumed in a bracket j attached to the tank) for imparting the upward or starting stroke to the water-lifting means. For imparting motion from handle i to the lifting means I may employ the rod o, and levers n 80 and p fulcrumed in bracket k, these parts being arranged and operating the same as in my Patent No. 1,109,971 above referred to, to which reference may be had for a more 85 particular description.

The piston h is constructed as follows: u is a disk which is fixed on the lower reduced end of the stem g by the nut v and has on both sides of the diametrical rib w the relatively large openings x. In the pairs of upstanding lugs y formed on the disk close to the rib w are arranged pintles z forming fulcra for the pivoted valves 2 each in the form of a substantially semi-circular plate having pairs of upstanding lugs 3 penetrated by the pintles and so arranged that when the valve is in the closed position its inner edge 2' underlies and may bear flat against the rib w while its outer edge 2'' overlies and may lie flat against the edge of the disk u at the outer side of the corresponding opening x. In the working stroke of the piston, therefore, the latter will be substantially closed at all points. Upon the piston reaching the end of the working 100 stroke, each valve will yield readily to the pressure of the water below (which is seeking to follow that displaced by the piston) 105

and remain fully open, because the area thereof relatively outward of the pivot z is somewhat greater than that relatively inward of said pivot. This condition will obtain until the pressure on the lower faces of the valves ceases, as when the piston has returned to the starting position and the outflow has stopped, whereupon gravity will return the valves at once to their seats, because even in their limits of opening movement, where they contact with the stem g , the offset relation of their pivots (in the lugs 3) brings the center of gravity of each valve outward of its pivot. When the lifting means is fully depressed (as in Fig. 1) it is desirable that the valve should be partly open, so that the shorter leg of the siphon may be duly supplied with the water necessary to start the siphon. I therefore provide the stops or detents 4 which are engaged by the undersides of the valves and tilt them slightly as the disk u approaches its downward limit of movement, such stops or detents being angular pins in the present case projecting inwardly from the cylindrical wall of the leg c .

I provide for pivoting the valves 2 in the peculiar manner described, *i. e.*, by employing the upstanding lugs 3 on each through which the pivoting axis extends, because thereby is obtained in a simple way the tendency of the valves when open to close promptly as soon as the action of gravity prevails; and by arranging each to overlap and underlap the disk at opposite sides of the opening the desired sealing or closing contact with the disk is accomplished in a way at once simple and effective.

The tube f limits the upward movement of the lifting means, it being abutted by the disk u at the end of the lifting stroke.

Any suitable inlet means, such as the nipple 5 having a valve 6 controlled by a float

carrying lever 7 all of well-known construction, may be employed.

45

Having thus fully described my invention, what I claim as new and desire to secure by Letters Patent is:—

1. In combination, a tank and means for effecting the discharge of the tank including a siphon constituting the discharge outlet of the tank, and a piston arranged in the short leg of the siphon, said piston including a stem protruding upwardly through the siphon and a disk attached to the stem and having an aperture at one side of the stem and a valve normally closing said aperture and pivoted on a horizontal axis elevated above the closing portion of and crossing the valve and being thereby adapted to swing to open position and being limited by the stem against open movement past its center of gravity, said valve overlapping the disk at one side, and underlapping the disk at the other side, of the aperture in said disk.

50

2. In combination, a tank and means for effecting the discharge of the tank including a siphon constituting the discharge outlet of the tank, a piston arranged in the short leg of the siphon, a stem carrying the piston and protruding upwardly through the siphon, said piston including an apertured disk and a valve pivoted on a horizontal axis in the disk and controlling the liquid flow through said aperture, and a stop to engage the under side of the valve in the downward movement of the piston, substantially as described.

55

In testimony whereof I affix my signature 60 in presence of two witnesses.

JOHN DENTON.
